Joseph P. Lavigne,
Inventor
By Atty
Earle Seymour

UNITED STATES PATENT OFFICE.

JOSEPH P. LAVIGNE, OF NEW HAVEN, CONNECTICUT, ASSIGNOR TO THE LAVIGNE & SCOTT MANUFACTURING COMPANY, OF SAME PLACE.

WRENCH.

SPECIFICATION forming part of Letters Patent No. 539,625, dated May 21, 1895.

Application filed February 18, 1895. Serial No. 538,751. (No model.)

To all whom it may concern:

Be it known that I, JOSEPH P. LAVIGNE, of New Haven, in the county of New Haven and State of Connecticut, have invented a new Improvement in Wrenches; and I do hereby declare the following, when taken in connection with the accompanying drawings and the letters of reference marked thereon, to be a full, clear, and exact description of the same, and which said drawings constitute part of this specification, and represent, in—

Figure 1, a view in side elevation of a wrench made in accordance with my invention; Fig. 2, an edge view thereof; Fig. 3, a detached view of the body or handle portion of the wrench stripped; Fig. 4, a view of the body or handle portion of the wrench in central longitudinal section; Fig. 5, a transverse sectional view of the wrench on line *a b* of Fig. 4.

My invention relates to an improvement in that class of small portable wrenches known as "monkey wrenches," the object being to provide at a low cost for manufacture, a simple, compact, strong, durable, convenient and effective wrench of attractive appearance.

With these ends in view, my invention consists in a wrench having certain details of construction and combinations of parts as will be hereinafter described and pointed out in the claim.

In carrying out my invention, I form in the handle or body-portion *A* of the wrench, a central, longitudinally arranged, elongated, transverse opening *B*, extending through it so as to cut through its opposite sides or faces. This opening is considerably narrower than the width of the rectangular shank *C*, at the respective ends of which the movable jaw *C'*, and the operating screw *C*² are located. In the opposite side walls of the said opening *B*, I form a pair of outwardly projecting transverse recesses *a a*, located opposite each other, a corresponding pair of outwardly extending recesses *a' a'* located opposite each other, and two inwardly projecting lugs *a² a²* located opposite each other, and interposed between the two pairs of recesses which lie between the longer and wider inner portion of the said opening, and the narrower and shorter outer portion thereof. I also form in the said por-

tion *A* of the wrench, a longitudinal opening *B'*, which extends inward from the face of the fixed integral jaw *A'* thereof, until it intersects the inner end of the transverse opening *B*. From the point of intersection of the openings *B* and *B'*, the latter is virtually extended to the recesses *a a*, in the form of two parallel longitudinal grooves *B² B²*, located opposite each other, and formed in the respective side walls of the inner portion of the opening *B*, the central portion of which they enlarge to equal in width, the width of the shank *C* before mentioned. The said shank *C* is located in the opening *B'*, in the wider and longer inner portion of the transverse opening *B*, and in the grooves *B² B²*, in the side walls of the said inner portion of the transverse opening. The operating-screw *C*² extends into the shorter, narrower outer portion of the transverse opening *A*, and more or less into the outer end of the wider inner portion of the said opening, according to the position of the shank in the body or handle portion of the wrench, in which the shank is held against flatwise or sidewise displacement by the side walls of the opening *B'*, and also by the side walls of the grooves *B² B²*, and against edge-wise displacement by the end walls of the opening *B'* and the end walls of the grooves *B² B²*. An operating-nut *D*, adapted to receive the said screw *C*², is constructed with two knurled shoulders *d d* respectively adapted to enter the recesses *a a* and *a' a'*, and with a circumferential groove *D'* located between the said shoulders, and adapted to receive the inwardly projecting lugs *a² a²*, whereby the nut is firmly held against endwise displacement, and has the purchase required for its operation upon the side walls of the grooves and lugs. The nut is held against sidewise displacement by the screw, which in turn is held against sidewise displacement by the shank which is maintained in position as already described.

My improved wrench in addition to other obvious advantageous qualities, is adapted to be produced at a comparatively low cost for manufacture, and presents a most attractive appearance, and on account of the open character of its body or handle portion, it is readily kept clean, as the same affords no lodgment for foreign objects.

It is apparent that in carrying out my invention, some changes over the construction shown and described may be made. Thus, if desired, the transverse opening may be uniform in width throughout its length. I do not, therefore, limit myself to the exact construction set forth, but hold myself at liberty to make such changes as fairly fall within the spirit and scope of my invention.

10 Having fully described my invention, what I claim as new, and desire to secure by Letters Patent, is—

15 In a monkey-wrench, the combination with a handle or body-portion having an integral fixed jaw, of a shank having a movable jaw formed integral with its inner end, and an operating screw formed integral with its outer end, and an operating nut adapted to receive the said screw, the said body-portion of the 20 wrench being constructed with a transverse opening extending nearly throughout its length, terminating within its inner and outer ends, passing transversely through it from side to side, and narrower than the width of

the said shank, with a longitudinal opening 25 intersecting at its outer end the face of the fixed jaw, and intersecting at its inner end the inner end of the said transverse opening to which it admits the said shank and screw, and corresponding in width and thickness to the 30 width and thickness of the said shank, and with two longitudinal grooves formed in the side walls of the inner end of the transverse opening and increasing the width of the central portion of the same to adapt the same to 35 receive the shank, the edges of which enter the said grooves, and the said body portion or handle being also transversely recessed at a point at or near the outer ends of the said grooves to receive the operating nut, substantially as described.

In testimony whereof I have signed this specification in the presence of two subscribing witnesses.

JOSEPH P. LAVIGNE.
